UNITED STATES PATENT OFFICE.

EDWIN L. RUSSELL, OF CLEVELAND, OHIO.

LUBRICATING-PUMP.

1,037,055.

Specification of Letters Patent. Patented Aug. 27, 1912.

Application filed December 15, 1911. Serial No. 665,946.

To all whom it may concern:

Be it known that I, EDWIN L. RUSSELL, a citizen of the United States, residing at Cleveland, in the county of Cuyahoga and State of Ohio, have invented a new and useful Lubricating-Pump, of which the following is a specification.

The object of my invention is to produce a very simple form of pump by means of which lubricating oil may be pumped to various bearings, the structure being especially designed for use in automobile engines and of such form that the pump chamber may be formed directly in a casing forming a portion of the engine casing or frame whereby stuffing boxes may be eliminated.

The accompanying drawings illustrate my invention.

Figure 1 is an elevation of an engine equipped with my improved pump, the pump and piston parts being shown in vertical section; Fig. 2 is a vertical sectional detail on a larger scale, approximately full size; Fig. 3 a section on line 3-3 of Fig. 2, with the pump shaft removed; Fig. 4 a fragmentary vertical section of the main stem of the pump and the associated pump head or disk; and Fig. 5 a section on line 5-5 of Fig. 2.

In the drawings, 10 indicates the lower casing member of the crank shaft casing 11 and this member is provided with an extension or boss 12 in which is formed a vertical axially tapered seat 13, which, at its upper end, communicates with the interior of the casing 10 substantially in alinement below a bearing 14 which is provided for the support of a valve-driving shaft 15. The seat 13 is upwardly tapered and at its lower end communicates with a pocket or pump chamber 16 (which in the form illustrated is cylindrical) from which leads a delivery passage 17 and into which leads a supply passage 18 which is formed within the body of casing 10 and communicates at its lower end with an oil reservoir 19. The pump chamber 16 is freely accessible at its lower end but is closed by a readily removable cap 21 in which is formed a spring pocket 22 in alinement with seat 13. The shank or shaft 23 of my pump fits at its lower end in the pocket 22 and upon this shank is slidably mounted a substantially circular disk or pump head 24. This pump head is provided with diametrically opposite radial slots 25 in each of which is mounted a ra-

dially movable piston or plunger 26 having an axial dimension equal to the axial dimension of the head 24. The two plungers 26 are normally urged outwardly by means of a spring 27 which extends through a passage 28 formed diametrically through shaft 23. Immediately above head 24 the shaft 23 is provided with an upwardly tapered bearing portion 29 which fits in pocket 13 and above this tapered portion is a tip 31 which carries a radially projecting pin 32 which in turn may be freely engaged by a pair of driving fingers 33 projecting downwardly from a nut 34 threaded upon the lower end 70 of shaft 15, the arrangement being such that no special care need be employed in having the seat 13 in exact alinement with shaft 15.

The tapered portion 29 of shaft 23 is held tightly in seat 13 by means of a spring 35 arranged within pocket 22 and within a pocket 36 formed in the lower end of shaft 23. Oil will gradually work into pockets 22 and 36 and therefore, in order to lubricate the tapered seat 13 and the bearing 29, I extend upwardly from the upper end of pocket 36 an oil passage 37 the upper end of which is projected to the face of the tapered bearing 29 at about midway of its length. 85 As the seat 13 wears, the bearing portion 29 will be projected upwardly into the seat and it is therefore necessary that the pump head 24 be connected to the shaft 23 in such manner as to permit this relative movement. 90 For that purpose, I project downwardly from the larger lower end of the bearing portion 29, a pair of pins 39 which are parallel with the axis of the shaft and project into corresponding openings 41 formed in 95 head 24.

In operation, it will be apparent that rotation of head 24 in a direction indicated by the arrow in Fig. 3 will cause a flow of oil from passage 18 to passage 17. I am well aware that a rotary pump of this general type is quite old but the feature of novelty in my present construction is the provision not of any special form of pump but of the tapered seat 13 and tapered bearing 29, with the automatic axially-adjustable connection between the shaft and the pump head so that an oil-tight connection may be maintained between the shaft and its bearing while at the same time making possible the axial filling of the pump chamber with the pump head without need for provision

of adjustment of those parts. By forming the pump chamber and its bearings directly in a casing member of the engine or crank case, it will be seen that I am able to wholly 5 avoid the necessity of packed shaft bearings for the pump.

I claim as my invention:

A pump system comprising a casing member having a pump chamber and a communicating axially tapered seat, of a pump shaft having a tapered portion journaled in said seat, a pump head having driving connection therewith mounted in the pump chamber

and carried by said shaft and having an automatically axially-adjustable driving 15 connection with said shaft, and means for holding the tapered portion of said shaft into the tapered seat.

In witness whereof, I have hereunto set my hand and seal at Indianapolis, Indiana, 20 this 11th day of December, A. D. one thousand nine hundred and eleven.

EDWIN L. RUSSELL. [L. S.]

Witnesses:

ARTHUR M. HOOD,
FRANK A. FAHLE.
